UNITED STATES PATENT OFFICE.

WALTER ERNI AND ARTHUR E. LANGE, JR., OF MILWAUKEE, WISCONSIN.

DESIGN FOR A COMBINED LAMP AND SOUND-REPRODUCING DEVICE.

Application filed June 8, 1922. Serial No. 2,571. Term of patent 3½ years.

To all whom it may concern:

Be it known that we, WALTER ERNI and ARTHUR E. LANGE, Jr., citizens of the United States, residing at Milwaukee, in the county of Milwaukee and State of Wisconsin, have invented a new, original, and ornamental Design for a Combined Lamp and Sound-Reproducing Device, of which the following is a specification, reference being had to the accompanying drawing, forming part thereof.

Fig. 1 is an elevation of the combined lamp and sound reproducing device.

Fig. 2 is an elevation drawn to a smaller scale and showing the hinged top tilted upwardly.

In the design shown, the sound reproducing apparatus is a phonograph, but it is obvious that either a phonograph or a wireless receiving device may be employed.

We claim:

The ornamental design for a combined lamp and sound reproducing device, as shown.

WALTER ERNI.
ARTHUR E. LANGE, JR.
